UNITED STATES PATENT OFFICE

160,483

INDUSTRIAL TRUCK

Robert H. Davies, Shaker Heights, Ohio, assignor
to The Baker-Raulang Company, Cleveland,
Ohio, a corporation of Ohio

Application December 19, 1949, Serial No. 6,703

Term of patent 14 years

(Cl. D14—3)

To all whom it may concern:

Be it known that I, Robert H. Davies, a citizen of the United States, residing at Shaker Heights, in the county of Cuyahoga and State of Ohio, have invented a new, original, and ornamental Design for an Industrial Truck, of which the following is a specification, reference being had to the accompanying drawings, forming part thereof.

Fig. 1 is a perspective view of an industrial truck, showing my new design; and Fig. 2 is a side elevation.

I claim:

The ornamental design for an industrial truck, as shown.

ROBERT H. DAVIES.
